LUBRICATING SYSTEM FOR SEWING
MACHINESClarence C. Smith, Chicago, Ill., assignor to Union
Special Machine Company, Chicago, Ill., a cor-
poration of Illinois

Application April 4, 1936, Serial No. 72,759

7 Claims. (Cl. 184—6)

This invention relates to lubricating systems for sewing machines.

Modern sewing machines, particularly industrial sewing machines, are complicated mechanisms designed for operation at high speeds, and their longevity and satisfactory performance is accordingly dependent upon proper lubrication at all times. With sewing machines as ordinarily constructed, lubrication was very often neglected due to the tedious and time consuming task of filling the numerous relatively inaccessible oil holes leading to the various working parts, and especially so since it necessitated stoppage of the machines. Moreover, forgetfulness on the part of the operators to lubricate any one of the many parts, resulted in the rapid wear of such parts with the necessity for frequent and costly replacements, as well as idling of the machines until the repairs could be made.

The chief aim of my invention is to preclude contingencies such as those to which attention has been directed above, which desideratum I realize in practice, as hereinafter more fully disclosed, through provision of a simple force feed lubricating system wherein a displacement means with a capacity greater than that required at any time serves to maintain a constant circulation of lubricating oil through and past the various moving parts of the sewing machine, and wherein the operating pressure is governed by overflow from the displacing means and the return of the excess oil to an original source of supply.

A further aim of my invention is to attain the foregoing advantages without wastage of lubricant through provision of efficient means for collecting the drip oil from the lubricated parts, straining out sediment and foreign matter and directing the recovered oil to the original supply source for re-use.

Another object of my invention is to provide, in connection with a lubricating system characterized as above, a simple and reliable means devoid of moving parts for visually indicating whether or not the system is functioning properly.

Other objects and corresponding advantages will appear from the following detailed description of the attached drawings, whereof

Fig. I is a view, partly in side elevation, and partly in longitudinal section, of a sewing machine conveniently embodying the lubricating system of my invention.

Fig. II shows the machine in front elevation.

Fig. III is a perspective view of a reservoir forming the source of oil supply for the lubricating system.

Fig. IV is a perspective view of a securing clip for the oil reservoir.

Fig. V is a view, partly in elevation and partly in axial section, of the drive shaft assembly of the sewing machine showing incorporated provisions for distribution of oil to bearings therefor and to various eccentrics mounted on said shaft.

Fig. VI shows the right hand end elevation of the shaft.

Fig. VII is a view partly in elevation and partly in axial section of a double eccentric and cam member associated with the drive shaft.

Figs. VIII and IX respectively are left and right hand end views of the double eccentric and cam member.

Fig. X is an axial sectional view of another eccentric associated with the drive shaft of the machine.

Fig. XI shows the right hand end view of the eccentric pictured in Fig. X; and

Figs. XII and XIII are views corresponding to Figs. X and XI of still another eccentric of the machine.

The sewing machine herein illustrated is generally of the type disclosed in Patent No. 1,751,508 granted to Norman V. Christensen and Frederick F. Zeier on March 25, 1930. Briefly described, the machine comprises a hollow base 1 whereof the top 2 serves as a work support, the machine being mounted on a sewing table indicated at 3. Rising from the base 1 is a standard 4 with laterally spaced front and rear projections 5 and 6 with inset bearing bushings 7 and 8 for a shaft 9 which is inclined somewhat to the horizontal, and to which, at the left hand or rear end, in Fig. I is secured a combined hand and belt wheel 10 so that the machine can be operated either manually or through a belt 11 with a motor or a power shaft (not shown) beneath the table 3. Confined to vertical reciprocation in a bushing 12 set into a forwardly-reaching projection 13 of the standard is a needle bar 14, which, at its lower end, carries a needle 15, the latter cooperating as usual with a looper or loopers (not shown) within the hollow of the machine base 1. Reciprocatory movement is imparted to the needle bar 14 through the medium of a link 16 by a dynamically-balanced integrally-formed crank disk 17 at the front end of the shaft 9. The looper or loopers and other parts within the hollow base 1 of the machine are actuated, through downward strap rod connections 18, 19, 20 and 21, by eccentrics 22, 23, 24 and 25 on the shaft 9. The presser foot 26 of the machine is in this instance carried by an arm 27 fulcrumed

on the machine frame, said presser foot being yieldingly urged downward by a presser bar 28 which is axially guided in the front projection 5 of the standard 4 and which at its lower end 5 bears upon said arm 27 as shown in Fig. I. The interval between the projections 5 and 6 of the standard 4 is closed by a separately attached cover 29 for protection of the moving parts within it.

10 The force feed circulating lubricating system with which the present invention is more especially concerned, comprises an oil reservoir 30 which is illustrated in perspective in Fig. III, said reservoir being of oblong rectangular configuration and provided at opposite ends with concaved projecting tongues 31. As shown in Figs. I and II, the oil reservoir 30 is suspended from the bottom of the table 3 beneath the sewing machine by clips 32 whereof one is illustrated 15 in perspective in Fig. IV, which are secured by screws 33 and which have concaved tongues 34 for underreaching the tongues 31 of said reservoir. Accordingly, when oil replenishment or renewal is necessary, the reservoir 30 can be easily 20 and quickly removed by lifting it slightly to disengage its tongues 31 from the concavities of the tongues 34 on the clips 32 and then moving it laterally to clear said clips. In the bottom of the hollow base 1 is a pan or sink 35 for engaging 25 drip oil from the lubricated parts of the machine. Centrally of the pan 35 is a drain pipe 36 which extends downward through an opening 37 in the table 3 into a subdivision set apart at one end 30 of the reservoir 30 by a transverse wire mesh partition 38. To the bottom end of the drain pipe 36 is detachably secured a strainer 39, so that the collected drip oil is thoroughly filtered 35 before it passes into the larger subdivision of the reservoir 30.

35 The oil is circulated in the system by action of a plunger piston 40 which reciprocates in the axial bore 41 of an integrally formed vertical boss 42 at the interior of the cover 29, see Fig. I, said bore being closed at the top by a removable screw plug 43. A helical spring 44 in compression between the bottom end of the boss 42 and a head 45 at the corresponding end of the plunger 40, yieldingly maintains said head in contact 40 with a rotary cam 46 centrally between and integrally formed with the eccentricities 22 and 23 (see Figs. I and VII) on the shaft 9. During the suction strokes of the plunger 40, oil is drawn 45 from the reservoir 30 through a tube 47 which extends upward to an intake check valve 48 at one side of the pump; and during the pressure 50 strokes of said plunger, the oil is forced past a check valve 49 at the opposite side of the pump, into a coiled tube 50 which connects with a vertical bore constituting a pressure chamber 51 within the projection 5 of the standard 4. From 55 the pressure chamber 51, the oil flows through a port 52 into an annular channel 53 (Fig. I) internally of the bearing bushing 7 and from thence, through a number of communicating 60 radial ports 54 in the shaft 9, to the axial bore 55 within the latter, said bore terminating inward of the left hand end of said shaft and being closed at its right hand end by a screw plug 56, all as shown in Figs. I and V. From the shaft 65 bore 55, the oil is distributed, by way of a number of other radial ports 57, 58, 59 and 60 to circumferential channels 61, 62, 63 and 64 interiorly of said eccentricities, see Figs. V and VI-XIII. It will be particularly noted that the internal 70 channels 61, 62, 63 and 64 within the eccentricities 75

22, 23, 24 and 25 are in themselves eccentric in respect to the shaft 9 and consequently the oil is forced from them by centrifugal action through radial ports 65, 66, 67 and 68 in said eccentricities to the outer surfaces of the latter. At its left hand end, the shaft 9 is provided with a radial port 69 which leads to the bore of the bearing bushing 8. As shown in Fig. I, the bearing bushings 7 and 8 are respectively formed at their left hand ends with annular gutters 70 and 71 which receive the oil that flows past the bearing surfaces. The annular gutter 70 in the bearing bushing 7 spills directly into the underlying pan or sink 35, while the oil from the annular gutter 71 in the bearing bushing 8 is directed to said trough or sink by a downwardly inclined duct 72 inwardly of the hollow base 1 and thereby prevented from spilling over onto the combined hand wheel and pulley 10.

As hereinbefore stated, the pump has a capacity in excess of the amount of oil requisite to adequate lubrication of the moving parts of the machine. Accordingly, provisions are made for returning such excess oil to the reservoir 30, these provisions including an overflow return pipe 75 which leads downward into the larger subdivision of said reservoir from a fitting 76 screwed into the upper end of the pressure chamber 51. Interposed in the fitting 76 is a sight glass 77, see Fig. II, which serves as a visible indicator whereby the operator can at all times see whether or not the system is functioning properly.

The machine herein shown and described is of course to be regarded as typical of other forms of sewing machines with which my improved force feed circulating lubricating system can be incorporated with attainment of advantages equal in all respects to those hereinbefore pointed out.

Having thus described my invention, I claim:

1. In a sewing machine comprising a shaft with a number of eccentricities thereon, and strap rods associated with the eccentricities for imparting motion to various instrumentalities of the machine mechanism; the combination of a force feed circulating lubricating system including an oil reservoir, a pump having a capacity greater than that required for the machine for drawing oil from the reservoir, a pressure chamber receiving the oil from the pump and communicating with an axial hollow of the shaft, from which hollow the oil is distributed by way of radial ports to eccentric channels around the shaft internally of the eccentricities and continually forced under centrifugal action from the deeper portions of said eccentric channels to the outer surfaces of the eccentricities, and provisions for returning the excess oil from the pressure chamber to the reservoir.

2. In a sewing machine comprising a shaft with a number of eccentricities thereon, strap rods associated with the eccentricities for imparting motion to various instrumentalities of the machine mechanism, and bearings for said shaft; the combination of a force feed circulating lubricating system including an oil reservoir, a pump having a greater capacity than that required for the machine for drawing oil from the reservoir, a pressure chamber receiving oil from the pump and communicating with an axial hollow of the shaft from which hollow the oil is distributed by way of radial ports to the shaft bearings, and by way of other radial ports to eccentric channels around the shaft internally of the eccentricities and continually forced under centrifugal action from

the deeper portions of said eccentric channels to the outer surfaces of the eccentrics, and provisions for returning the excess oil from the pressure chamber to the reservoir.

5. In a sewing machine comprising a hollow base, a standard rising from the base and affording spaced bearings for a shaft with rotary members thereon between said bearings for actuating various instrumentalities of the sewing machine 10 within the hollow of the base, and a cover closing the space between said bearings; the combination of a force feed circulating lubricating system including an oil reservoir beneath the machine base, a pump chamber afforded by the cover aforesaid, a pump piston actuated from the shaft and effective to draw oil in excess of that required for the machine, means for conducting oil from the pump to a pressure chamber in one of the bearings, said pressure chamber being in communication with an axial hollow of the shaft wherefrom the oil is distributed by way of radial ports to the shaft bearings and to the rotary members aforesaid, and provisions for returning the excess oil from the pressure chamber to the 25 reservoir.

4. In a sewing machine, a hollow drive shaft with radial ports at intervals along its length; eccentrics on the shaft; strap rods associated with the eccentrics for actuating various instrumentalities of the machine mechanism, said eccentrics having internal grooves providing eccentric channels around the shaft respectively in registry with the radial ports of the latter, and having ports leading from said eccentric channels to their strap bearing surfaces; and means for delivering lubricant into the hollow of the shaft for distribution by way of its radial ports to the eccentric channels within the eccentrics, and from thence continually by centrifugal action from the deeper portions of said channels through the ports in said eccentrics to the strap bearing surfaces.

5. In a sewing machine, a hollow drive shaft with radial ports at intervals along its length; bearings in line with the endmost ports in which the ends of the shaft are journaled; a chamber for lubricant above one of the bearings and communicating laterally with an annular channel around the corresponding endmost radial port of the shaft; a plurality of eccentrics on the shaft in the interval between the bearings, said eccentrics having internal grooves providing eccentric channels around the shaft which respectively register with the intermediate radial ports of the latter, and ports leading from said eccentric

channels to the eccentric bearing surfaces; and means for delivering lubricant under pressure into the hollow of the shaft for distribution by way of the endmost radial ports of the latter to the shaft bearings, and by way of the intermediate radial ports to the eccentric channels within the eccentrics, and continually forced from the high points of said channels under centrifugal action through the ports in said eccentrics to the eccentric bearing surfaces.

6. In a sewing machine, a hollow drive shaft at an inclination to the horizontal having radial ports at intervals along its length; bearings in line with the endmost radial ports in which the ends of the shaft are journaled; a chamber for lubricant above the higher of the two bearings and communicating with an annular channel around the corresponding endmost radial port of said shaft; and a plurality of eccentrics on the shaft in the interval between the bearings, said eccentrics having internal grooves providing eccentric channels around the shaft which respectively register with the intermediate radial ports of said shaft, and ports leading from said eccentric channels to the eccentric bearing surfaces,

whereby the oil is continually forced under centrifugal action from the high points of said channels to said bearing surfaces.

7. In a sewing machine, a hollow drive shaft with radial ports at intervals along its length; bearings in line with the endmost radial ports in which the ends of the shaft are journaled; a chamber for lubricant above one of the bearings and communicating with an annular channel around the shaft at the corresponding endmost radial port of the latter; a pump above and adjacent the other shaft bearing; a plurality of eccentrics on the shaft in the interval between the bearings, said eccentrics having internal grooves providing eccentric channels around the shaft which register respectively with the intermediate radial ports of the latter, and ports leading from said eccentric channels to the eccentric bearing surfaces; a lubricant reservoir at a level beneath the shaft; and means on the shaft for actuating the pump aforesaid to draw lubricant from the reservoir and deliver it under pressure into the lubricant chamber for distribution, by way of the hollow of the shaft and its radial end ports, to the shaft bearings and to the eccentric channels within the eccentrics and continually forced from the high points of said channels under centrifugal action through the ports in said eccentrics to the eccentric bearings.

CLARENCE C. SMITH.
